[57] **CLAIM**

The ornamental design for pavement marker, as shown
and described.

DESCRIPTION

FIG. 1 is a perspective view of a compact pavement
marker showing a new design and with the broken line
showing for illustrative purposes only and forming no
part of the claimed design;

FIG. 2 is a top elevational view thereof;

FIG. 3 is a left side elevational view, with the opposite
side being a mirror image;

FIG. 4 is a front elevational view thereof; and,

FIG. 5 is a bottom elevational view thereof.
